UNITED STATES PATENT OFFICE.

GEORGE COLBY MACKROW AND HERBERT GEORGE CAMERON, OF LONDON,
ENGLAND.

APPARATUS FOR SHUNTING SUSPENDED LOADS FROM ONE TRACK OR POSITION TO ANOTHER.

SPECIFICATION forming part of Letters Patent No. 674,651, dated May 21, 1901.

Application filed January 8, 1901. Serial No. 42,546. (No model.)

To all whom it may concern:

Be it known that we, GEORGE COLBY MACKROW and HERBERT GEORGE CAMERON, subjects of the King of Great Britain, residing 5 at Orchard Yard, Blackwall, London, England, have invented a new and useful Apparatus for Shunting Suspended Loads from One Track or Position to Another, of which the following is a specification.

10 The object of this invention is to provide a means for transferring and depositing a load (which may be in the first place either stationary or moving) onto or from a traveling line or rope and in such a manner as to avoid 15 any considerable shock during the operation.

According to our invention we employ a special form of automatic grip-hook for carrying the load, a shunt-bar along which the said hook travels with the load to or from the 20 traveling line, and a striking plate or bar for causing the grip-hook to disengage from the traveling line.

In carrying out our invention we construct a duplex hook, one of which hooks is a slip or 25 trip hook designed to engage with the traveling line and to be disengaged therefrom by the striking-plate, the other being a fixed hook for the purpose of engaging with the shunt-bar. In the slip or disengaging hook the face 30 of the slipping tongue forms an acute angle with the face of the stock or main part of the hook, so that the line or rope which it is designed to grip cannot get right up into the throat, but becomes wedged in between the 35 tongue and stock or main part, whereby the hook is caused to grip the line to prevent sliding. This slipping tongue is held in its normal position by a spring trigger or catch, which by coming into contact with the striking-plate releases the hook from the traveling line and allows it to engage the shunt-bar, the slipping tongue and trigger then returning 40 to their normal positions under the action of a spring. The shunt-bar in addition to carrying the load during the time it is being transferred from one point to another, after having been disengaged from or previous to engaging with a moving line, also serves to 45 alter the direction of motion of the load when necessary, and at the same time to allow the

speed at which the load may be traveling when it reaches the bar being regulated as it passes over the said bar or of being brought to a standstill.

The above regulation of speed may be effected by inclining the shunt-bar so that the load in sliding down it attains the required speed. 55

Although the slip-hook is mainly intended to engage directly with a traveling line, it may 60 engage it indirectly.

To enable the invention to be fully understood, we will describe how it can be carried into practice by reference to the accompanying drawings, in which— 65

Figure 1 is a sectional side elevation of an arrangement of apparatus constructed according to our invention for shunting suspended loads from one track to another. Figs. 2 and 3 are respectively a sectional end elevation 70 and a sectional plan of the same. Figs. 4 and 5 are respectively views at right angles of a detail drawn to a larger scale than Figs. 1, 2, and 3. Figs. 6 and 7 are respectively a side elevation and a plan of another arrangement 75 of our apparatus, and Figs. 8 and 9 are similar views of another arrangement. Figs. 10 and 11 are views at right angles to each other, respectively, of the grip-hook; and Fig. 12 is a sectional side elevation of the same. Figs. 80 10, 11, and 12 are drawn to a larger scale than the remaining figures.

Similar reference-letters indicate similar or corresponding parts throughout the drawings. 85

a, Figs. 1, 2, 3, 6, 7, 8, and 9, is a traveling line working in a horizontal direction and passing around pulleys, one of which is shown at *a'*, Fig. 8, and *b*, Figs. 1, 2, and 3, is a traveling line working in a vertical direction 90 and serving to feed the line *a* with the load, as hereinafter described. The line *b* consists of two ropes or chains working over pulleys *c c* and carrying between them cross-shafts *d d*, having rollers *e e* on their ends working 95 in guides *f f* in a casing *g*, the said shafts being provided with shackles *h h* for the attachment of the load *i*.

j, Figs. 1, 10, 11, and 12, is our duplex hook carrying the load *i*, and *k* is the inclined 100

shunt-bar which in Figs. 1 to 3 serves to divert the load *i* from the line *b* to the line *a*, while in Figs. 6 and 7 and 8 and 9 it serves to divert the load from the line *a*.

5 *l*, Figs. 10, 11, and 12, is the slip or disengaging hook of the grip-hook *j*, and *m* is the fixed hook. The said hook or tongue *l* is pivoted at *n* within a slot *o* in the stock or body *p*, and *q* is the spring-catch for locking the said tongue in the position shown by the full lines in Figs. 10 and 12, the said catch being pivoted to the stock *p* at *p'*. The inner face of the tongue *l* forms an acute angle with the stock *p*, so that the rope *a* when engaged therewith becomes wedged between the said parts, as shown by the dotted lines in Figs. 10 and 12, and so the hook cannot slip thereon.

7 *r* is the striking-plate against which the spring-catch *q* comes into contact, as herein-after described, to disengage the said catch from the tongue *l*, and thus release the latter from the line *a* or the like supporting it and allow the fixed hook *m* to engage with a shunt-bar, the said tongue turning on its pivot to about the position indicated by dotted lines in Fig. 12.

l' is a spring for returning the tongue *l* to its normal position against a stop *l''*.

30 In Figs. 1 to 3 the shunt-bar *k* has one end extending within the casing *g* and in position for the engagement therewith of the fixed hook *m* of each grip-hook *j*, carried by the cross-shafts *d d* of the vertically-traveling line, and has the striking-plate *r* in close proximity to it. The said shunt-bar is connected to the casing *g* by a bracket *s*, and the other end is pivoted to a frame *t*, carrying rollers *u u*, engaging the line *a*. In order that the bar *k* can move in accordance with any oscillatory movements of the rope *a*, it is connected to the bracket *s* by a universal joint *v*. (Shown clearly in detail at Figs. 4 and 5.) In Figs. 6 and 7 the shunt-bar is connected to the line *a* at one end, in a similar manner to that of the shunt-bar shown in Figs. 1, 2, and 3; but it is provided with two horns *k' k'* for guiding the hook *j* to the bar *k*, and the striking-plate is also arranged at this end. 45 The other end of the bar is connected by the universal joint *v* at a point below the line *a*. In Figs. 8 and 9 the shunt-bar is also provided with the horns *k' k'*, as in Figs. 6 and 7, and is connected at one end to one end of 50 an arm *w*, pivoted at the other end to the bearing of the pulley *a'*, the said arm *w* carrying a roller *x*, which bears upon the line *a*, and thus maintains the end of the shunt-bar in its proper relative position with the said line *a*. The striking-plate *r* is also carried by the arm *w*.

The operation of our improved apparatus shown in Figs. 1 and 3 is as follows: The loads *i* carried by the traveling line *b* successively 65 pass the striking-plate *r*, so that the spring-catch *q* on each duplex hook *j* comes into contact with the said plate *r* and is disengaged

from the slip-hook *l*, so that the latter is released from the shackle *h* and allows the fixed hook *m* to bear upon the shunt-bar *k*, down which the load slides by gravity and engages the traveling line *a* by means of the slip-hook, the shunt-bar being at such an inclination that the load attains about the same speed as that of the line *a* by the time it reaches the latter, 75 so as to avoid shock. The load is then carried by the line *a* until the spring-catch on its grip-hook comes into contact with another striking-plate *r*—for instance, that shown in Figs. 6 and 7 or Figs. 8 and 9—when it is 80 caused to leave the line *a* and become engaged with the shunt-bar in connection with the said striking-plate. The load then slides down the said shunt-bar to any required position. By forming the shunt-bar so that one 85 portion assumes a horizontal position the load can be brought to rest on the said bar.

Having now particularly described and ascertained the nature of our said invention and in what manner the same is to be performed, 90 we declare that what we claim is—

1. The combination with a traveling line or rope for carrying loads of an inclined bar or bars for supporting or guiding the loads onto or from the line, of a duplex hook for suspending the loads, one hook of which designed to engage with the line is formed with a movable tongue normally locked by a spring-catch, the other hook being rigid and designed to engage with the inclined bar and a 95 plate with which the said catch comes into contact to release the movable hook from the line, substantially as and for the purpose, set forth.

2. In transporting apparatus, the combination with a traveling line, of an inclined guide-bar for supporting or guiding loads onto or from the line, a universal joint connected to one end of said guide-bar and to a fixed support, and devices connected to the other end of said bar and engaging the line, substantially as described.

3. In transporting apparatus, the combination with a traveling line, of an inclined guide-bar having one end adjacent to said line, and a duplex load-carrying hook provided with a hook for engaging said guide-bar and a hook for engaging said line, substantially as described.

4. In transporting apparatus, the combination with a traveling line, of an inclined guide-bar having one end adjacent to said line, a duplex load-carrying hook provided with a hook for engaging said guide-bar, a pivoted hook for engaging said line, and a locking device for said pivoted hook, substantially as described.

5. In transporting apparatus, the combination with a traveling line, of an inclined guide-bar having one end adjacent to said line, a duplex load-carrying hook provided with a hook for engaging said guide-bar, a pivoted tongue forming an acute angle with a part of the hook-body, when in operative position, to

clamp the said line, and cause the hook to travel therewith, and a locking device for said pivoted tongue, substantially as described.

6. In transporting apparatus, the combination with a traveling line, of an inclined guide-bar having one end adjacent to said line, a duplex load-carrying hook provided with a hook for engaging said guide-bar, a pivoted tongue for engaging said line, and a detent for holding said pivoted tongue in operative position, and a striking-plate adjacent to one end of said guide-bar in position to engage said detent, substantially as described.

7. In a transporting device, the combination with a traveling endless line, of a guide-bar inclined to the path of said line, and having its lower end adjacent to the line, and a duplex load-carrying hook having a hook for engaging the line and a hook for engaging said guide-bar, whereby said duplex hook and its

load will acquire initial speed while sliding down said guide-bar so as to avoid shock in transferring to the moving line, substantially as described.

8. In a transporting device, the combination with a traveling endless line, of a guide-bar inclined to the path of said line and having its lower end adjacent to the line, a second inclined guide-bar located at a distance from the first-mentioned guide-bar and having its upper end adjacent to the line, and a duplex load-carrying hook having a hook for engaging the said guide-bars and a separate hook for engaging the traveling line, substantially as described.
